UNITED STATES PATENT OFFICE.

CHARLES P. CORLISS, OF ELGIN, ASSIGNOR TO THE ELGIN NATIONAL WATCH COMPANY, OF CHICAGO, ILLINOIS.

STOP-WATCH.

SPECIFICATION forming part of Letters Patent No. 339,862, dated April 13, 1886.

Application filed August 28, 1884. Serial No. 141,651. (Model.)

To all whom it may concern:

Be it known that I, CHARLES P. CORLISS, of Elgin, in the county of Kane, and in the State of Illinois, have invented certain new and useful Improvements in Stop-Watches; and I do hereby declare that the following is a full, clear, exact description thereof, reference being had to the accompanying drawings, in which—

10 Figure 1 is a perspective view of the front or dial side of a movement having my improvements, a portion of the dial being broken away to show the supplemental minutes-hand arbor. Fig. 2 is a like view of the opposite 15 side of the same. Fig. 3 is an enlarged perspective view of the winding-arbor and sectional sleeve separated from each other. Fig. 4 is a like view of the same combined. Fig. 5 is an enlarged perspective view of the parts 20 which furnish a bearing for the seconds-arbor, separated from each other. Fig. 6 is a like view of the same combined. Fig. 7 is an enlarged perspective view of the combined ratchet and cam wheels and their connecting parts, 25 and Fig. 8 is an enlarged section upon line *x* of Figs. 1 and 2.

Letters of like name and kind refer to like parts in each of the figures.

My invention relates to improvements in 30 stop-watches; and it consists, principally, in the means employed for enabling the timing-hands to be started, stopped, and set at zero, substantially as and for the purpose hereinafter specified.

35 It consists, further, as an improvement in stop-watches, in a supplemental minutes-hand arbor journaled at or within the axis of the main wheel of the winding attachment, substantially as and for the purpose hereinafter 40 shown and described.

It consists, finally, as an improvement in stop-watches, in a supplemental minutes-hand arbor, which is journaled within the axis of the main wheel of the winding attachment in 45 a line with the axis of the winding-arbor, substantially as and for the purpose hereinafter 50 specified.

In the annexed drawings, A represents the front or pillar plate of a watch, and B the back 55 plate or winding-bridge, which parts are constructed and combined in the usual manner.

Journaled between the plate A and bridge B is a winding-arbor, C, which at its outer end is adapted to engage with a push-pin, D, and at its inner end is provided with a pinion, e, 55 that meshes with and imparts motion to a toothed wheel, E, which is pivoted upon the outer face of said plate A, and constitutes the main wheel of the winding attachment. The wheel E is preferably pivoted upon a boss that 60 is formed upon the plate A, and is held in position thereon by means of a washer, e, and screw e'; but any desired construction may be used for pivoting said wheel in place.

Journalized within the plate A and bridge B, 65 at the axis of the winding-wheel E, and in a line with the axis of the winding-arbor C, is an arbor, F, which upon its front end carries a hand, f, and, being suitably connected with the time-train, operates to register minutes 70 upon a supplemental dial, g, that is provided within the ordinary dial, G. Such location of said supplemental arbor in no manner interferes with the ordinary time-train of a watch, and renders practicable the utilization of such 75 time-train without change in the construction of a stop-watch, while otherwise a special movement differently arranged would be necessary.

The longitudinal movement of the push-pin 80 D is employed for starting, stopping, and setting at zero the timing-hands, and as a means for communicating motion from the former to the latter I employ a sleeve, H, which is placed upon and adapted to move lengthwise of the 85 winding-arbor C between the plate A and bridge B, and is held outward with a yielding pressure by means of a spring, I. The outer end of said sleeve impinges upon the inner side of the case-spring K, and the inner end of 90 said push-pin upon the outer side of the same, while upon an arm, h, that projects from said sleeve radially rearward through said bridge is pivoted a pawl, h', which engages with a ratchet-wheel, L, and when the push-pin is 95 moved inward rotates said wheel a distance equal to the circumferential length of one of its teeth. Upon the outward movement of said sleeve said pawl trips over and engages with the next succeeding tooth, and is then in 100 position for effecting a farther partial revolution of said ratchet-wheel when said push-pin

is again moved inward. The ratchet-wheel L carries upon its outer face a cam-wheel, M, which has contact at its notched periphery with levers N, O, and P for starting, stopping, 5 and setting the hand-carrying arbors at zero, said mechanism being of any usual form or construction.

In order that variations in the thickness or position of the case-spring K may be compensated and the movement readily adjusted to a case, the sleeve H has its interior made considerably larger than the winding-arbor C, and is provided with a screw-thread. Into said threaded interior is placed a second exteriorly-threaded sleeve, h^2 , which fits loosely upon said winding-arbor, and is preferably split longitudinally a portion of its length, so as to cause it to be firmly held in place by the outward spring of its divided portion, while 15 free to be rotated by means of a screw-driver. The outer end of the inner sleeve, h^2 , now forms the bearing against the case-spring K, and by turning the former within the sleeve H its said bearing end may be extended or retracted as much as may be necessary to adapt it to the position or thickness of said spring. 20

In open-face watches, where no case-springs are used, the bearing end of the adjustable sleeve is extended to and receives the inner 25 end of the push-pin.

The construction described enables the stop-watch movement to be easily and quickly fitted to and placed in any case for which it is adapted without other change than can be produced 30 by means of a screw-driver.

Having thus fully set forth the nature and merits of my invention, what I claim as new is—

1. As an improvement in stop-watches, the 40 combination, with mechanism for returning the timing-hands to zero, and with a push-pin that is journaled within the case-stem, of a

sleeve which surrounds the winding-arbor and is engaged by said push-pin, and a pawl that is pivoted only upon said sleeve and is adapted 45 to engage with a ratchet-wheel, whereby the longitudinal movements of said push-pin will be communicated to and cause a step-by-step rotation of said ratchet-wheel, substantially as and for the purpose specified. 50

2. As an improvement in stop-watches, the combination of a push-pin which is journaled within the case-stem, a sleeve that encircles the winding-arbor and is engaged by said push-pin, a pawl which is pivoted only upon said sleeve, a ratchet-wheel that is engaged by said pawl and by rotation is adapted to actuate mechanism for starting, stopping, and returning the timing-hands to zero, and a spring which operates to hold said sleeve with a yielding pressure at the outer limit of its motion, whereby the longitudinal motion of said push-pin will cause a step-by-step rotation of said ratchet-wheel, substantially as and for the purpose shown. 60

3. As an improvement in stop-watches, a supplemental minutes-hand arbor journaled at or within the axis of the main wheel of the winding attachment, substantially as and for the purpose shown and described. 70

4. As an improvement in stop-watches, a supplemental minutes-hand arbor which is journaled within the axis of the main wheel of the winding attachment in a line with the axis of the winding-arbor, substantially as and for 75 the purpose specified.

In testimony that I claim the foregoing I have hereunto set my hand this 21st day of July, A. D. 1884.

CHARLES P. CORLISS.
